UNITED STATES PATENT OFFICE

152,504

DESIGN FOR A PROJECTION APPARATUS

James Y. Taylor and Carl C. Taylor, Garland, Tex., assignors to J. Y. Taylor Company, Garland, Tex., a partnership composed of James Y. Taylor and David D. Simpson

Application August 18, 1948, Serial No. 148,168

Term of patent 14 years

(Cl. D61—1)

To all whom it may concern:

Be it known that we, James Y. Taylor and Carl C. Taylor, citizens of the United States, residing at Garland, in the county of Dallas and State of Texas, have invented a new, original, and ornamental Design for Projection Apparatus, of which the following is a specification, reference being had to the accompanying drawings, forming part thereof.

Fig. 1 is a front perspective view of a projection apparatus, embodying the design;

Fig. 2 is a side view thereof; and

Fig. 3 is a rear perspective view thereof.

In the drawings the characteristic features of our design are shown in full lines.

We claim:

The ornamental design for a projection apparatus, substantially as shown and described.

J. Y. TAYLOR.

CARL C. TAYLOR.
